Primary Examiner — Jeffrey D Asch*Assistant Examiner* — Tracey J Bell(74) Attorney, Agent, or Firm — Leydig, Voit & Mayer, Ltd.(57) CLAIM

The ornamental design for a shoe, as shown and described.

DESCRIPTION

FIG. 1 is a top right front perspective view of the shoe showing my new design;

FIG. 2 is a bottom view thereof;

FIG. 3 is a rear view thereof;

FIG. 4 is a front view thereof;

FIG. 5 is a right side view thereof;

FIG. 6 is a left side view thereof; and,

FIG. 7 is a top perspective view thereof.

The broken lines in the drawings disclose the environment related to the claimed design, but form no part of the claimed design.

1 Claim, 7 Drawing Sheets(56)
